APPARATUS FOR AND METHOD OF AIR CONDITIONING

Philip Sherman Russel, Detroit, Mich., assignor to
 Detroit Lubricator Company, Detroit, Mich., a
 corporation of Michigan

Application May 14, 1935, Serial No. 21,353

25 Claims. (CL 236—44)

My invention relates in general to the method of and apparatus for conditioning the air in a room or other enclosed space, and more particularly to the method of and apparatus for controlling the relative humidity of the air in a room or other enclosed space.

One of the objects of my invention is to provide a new and improved method of and apparatus for maintaining the highest possible relative humidity of the air in a room or other enclosed space for all outdoor temperatures below a given predetermined degree of temperature without resultant precipitation of the moisture of the room air on a window pane or other heat transmitting room wall surface.

Another object of my invention is to provide a new and improved method of and apparatus for controlling the heating of a room or other enclosed space in a manner so that the supply of heat to the room is expedited and the time period following the demand for heat by the room thermostat or other controlling device is decreased, and to also prevent the temperature of the room air from being heated to a degree of temperature excessively above that for which the thermostat is set.

Another object of the invention is to provide a new and improved method of and apparatus for maintaining a given predetermined desired humidity in a room for all outdoor temperatures above a predetermined degree of temperature to prevent dehumidifying the air of the room to a point in excess of that necessary for comfort.

Another object of my invention is to provide a new and improved method of and apparatus for preventing stagnation of the air in a room or other enclosed space and resultant cold zone at the floor of the room on the "off" phase of the burner.

The invention consists in the method of control and the device or apparatus for performing the same, to be more fully described hereinafter and the novelty of which will be particularly pointed out and distinctly claimed.

In the accompanying drawings, to be taken as a part of this specification, I have fully and clearly illustrated an air conditioning system and the apparatus for controlling the same by which my method may be performed, in which

form of my air conditioning system embodying other features of my invention:

Fig. 3 is a detail view showing the manner of arranging temperature and humidity control devices of the air conditioning system, with a window pane of a room;

Fig. 4 is a plan view of Fig. 3, and

Fig. 5 is an enlarged view of the temperature and humidity control device employed in the system of Fig. 2.

Fig. 6 is a view similar to Fig. 3 showing another arrangement of the temperature and humidity control device relative to a window pane.

When cold outdoor air of any relative humidity is heated to a temperature of 70° F., its relative humidity decreases and it is the consensus of opinion that if the air of a room is heated to a temperature of 70° F., the relative humidity of the room air should, from the standpoint of health and comfort, be maintained at 40% relative humidity. It is well known that at low outdoor temperatures it has not been possible to maintain the air of a room at 40% relative humidity without condensation of room air

moisture on a window pane or other heat transferring room wall surface. When outdoor temperature is below that which will permit the maintenance of the room air at a relative humidity of 40% without condensation taking place

on a window pane, the nearest approach to the desired 40% relative humidity of the room air without condensation taking place may be obtained by maintaining a relative humidity of the room air at the window pane just under 100% relative humidity. It is likewise advisable that when the outdoor temperature is above a predetermined temperature that the maintenance of the room air at the window pane at 100% relative humidity be discontinued.

When the outdoor temperature has increased above a predetermined temperature, the normal relative humidity of the outdoor atmosphere will not be sufficiently decreased by room heating to make artificial humidification of the room air advisable. Also, when outdoor temperature has increased to a point where indoor heating is unnecessary, and to a point where indoor temperatures become uncomfortable, an improved comfort condition may be obtained by the dehumidifying of the room air.

Referring now to the drawings for a more detailed description of my invention, and more particularly to Fig. 1, there is shown an air conditioning system for conditioning the air of a room or other enclosed space and this system

Figure 1 is a diagrammatic view of an air conditioning system embodying features of my invention;

Fig. 2 is a diagrammatic view of a modified

includes a heating apparatus 1, a humidifying apparatus of which only the moisture supply control device 2 is shown, a motor 3 of a dehumidifying apparatus (not shown), and control means designated in general at 4 for controlling the operation of the heating, humidifying and dehumidifying devices. Preferably the heating apparatus is of the oil burning type having a burner (not shown) preferably driven by an electric motor 6. The control mechanism 4 comprises in general a thermostat 7 and a humidostat including a moisture absorption element 8 expandible and contractible in accordance with the moisture content of the ambient or surrounding air. The humidostat and thermostat are preferably mounted on a supporting member, preferably a panel or board 9, and the board 9 is preferably secured on or arranged in close proximity to a window pane 10, Fig. 3, or other heat transmitting room wall surface so that the thermostat is affected by outdoor temperature and the humidostat element is affected by the moisture content of the room air cooled by outdoor temperatures.

The thermostat 7, in the present system, by reason of its arrangement with the window pane 10 is in good heat transfer relation with outdoor temperature. It will also be seen that the humidostat expandible-contractible element 8 is in the path of circulating room air and is responsive to the moisture content of the room air but at outdoor temperatures because of its arrangement adjacent the window pane at which point the room air is cooled by and substantially to outdoor temperatures.

Preferably the air conditioning apparatus is electrically operated, the humidostat including a contact or switch arm 12 pivotally mounted on the board 9, as at 13, and provided on its free end and on opposite sides thereof with insulated contacts 14 and 15. The expandible-contractible element 8 is preferably located at one side of the lever arm 12 and with one end abutting the arm 12 preferably near its pivot point 13 so that relatively small expansion or contraction of the element 8 will result in the free end of the lever being moved through a relatively large arc. A spring 16 having one end fixed to the lever 12 and the other to the board 9 is under tension to maintain the lever 12 in engagement with the end of the expandible-contractible element 8.

A contact supporting member which may be in the form of a plate 17 is pivotally mounted on the supporting board 9 and carried by the plate 17 are two spaced contacts 18 and 19, one on each side of the lever arm 12, and arranged to be engaged by the contacts 14 and 15 respectively of the lever arm 12. Preferably the plate 17 is provided with a handle 20 by means of which it may be pivoted and by so doing, position one or the other of the contacts 18 and 19, carried thereby, closer to or farther away from its respective contact 14 or 15 of lever 12. In winter, the contact 14 of the lever 12, cooperates with contact 18 to make and break the circuit through expansion or contraction of the element 8 while in summer, the contact 15 of lever 12 cooperates with contact 19 to make and break the circuit. The contacts 18 and 19 are preferably individually adjustable relative to their respective contacts 14 and 15 of lever 12 so as to provide for obtaining a second and more accurate spacing between the contacts. To this end contacts 18 and 19 may be fixed on the ends 75

of screws 21 threaded in bosses formed on the plate 17. The thermostat 7 has a bimetallic element or arm 22 movable in response to change in outdoor temperature, and on the free end of the arm 22 and on opposite sides thereof are provided contacts 23 and 24. Mounted on the board 9 are spaced contacts 25 and 26, one on each side of the arm 22 for engagement by the contacts 23 and 24 respectively of the arm 22.

As shown in Fig. 4, the supporting board 9 is provided with substantially parallel side members or flanges 27, and preferably the supporting board 9 is arranged in relation to the window pane 10 so that the longitudinal edges of the side members 27 are against or in close proximity to the inner side of the window pane 10. The window pane 10 thus cooperates with the inner walls of panel 9 and its side members 27 to define a chamber 28, the top and bottom of which is open for the passage of air therethrough. The thermostat and humidostat are mounted on the inner wall of panel 9 within the chamber 28. By reason of the window pane forming one side of the control device housing, it will be understood that the room air in or passing through chamber 28 is cooled by outdoor temperature transmitted to the chamber or space 28 by the heat transmitting window pane 10 and that the temperature within chamber 28 is substantially the same as the outdoor temperature and varies in accordance with change in outdoor temperature, with the result that the thermostat is responsive to changes in outdoor temperature. Likewise the humidostat element 8 is operable in response to change in the moisture content of the room air but at the temperature of the air passing through chamber 28. The air flow through chamber 28 is the result of a down draft of air from the relatively cold window pane.

In order to support the board 9 in relation to the window pane 10 so that the thermostat and humidostat will be in good heat transfer relation with the outdoor temperature and also so that ready access may be had to the thermostat and humidostat without necessity of removing screws or other attaching means, I provide a hinge 29 for supporting the board 9 and a spring 30 for resiliently maintaining the board 9 against the window pane 10, as shown in Fig. 4. The hinge 29 may be of any suitable type and has one side or leaf fixed to the board 9, and the other side or leaf fixed to the window frame 29a, such as by screws. The spring 30, which may be a coiled spring, has one end fixed to the pivotal side of the hinge with the other end fixed to the other side of the hinge and so positioned as to exert a force on the pivoted side to urge the same toward the window pane. When it is desired to adjust the thermostat or humidostat, it will be seen that ready access may be had thereto by swinging the hinged panel 9 away from the window pane. When the board or panel 9 is swung away from the window to the point where the spring is moved over center, it will be seen that the spring then acts to hold the board 9 away from the window. By providing a hinged board, as above described, for supporting the thermostat and humidostat relative to a window pane, it will be appreciated that the window pane can be washed without inconvenience since the board can be swung out of the way and also if desired the window can be opened without necessity of removing screws or other attaching means.

The contact 25 of the thermostat is connected by a lead wire 32 to one end of the usual coil 33^a of a relay switch 33. The other end of coil 33^a is connected to one side of the secondary of a transformer 34. The other side of the secondary of the transformer is connected by a lead wire 35 to the bimetallic element 22 and therethrough to contact 23. A lead wire 37 connects the wire 32 to the contact 14 of the humidostat lever 12 and a lead wire 38 connects the contact 26 of the thermostat to the contact 15 of the humidostat. The control device 2 of the humidifying or moisture supply apparatus is located in the moisture supply line or pipe 39 and includes a valve for controlling the admittance of moisture to the air of a room. Preferably the valve is electrically operated such as by a solenoid having the usual movable core 40 surrounded by a coil 41. As shown, the valve may be an integral part of the core, if desired, and in the present arrangement is moved to open the valve port when the coil 41 is energized and moves by gravity to close the valve port when the coil 41 is deenergized. The coil 41 is connected by a lead wire 42 in series with contact 18 of the humidostat device and the secondary of the transformer 34. A manually operated switch 42^a may be provided in lead wire 42 between the control valve and the secondary of the transformer by means of which the circuit to the valve may be opened manually.

The dehumidifying device may be of any suitable type, the motor 3 preferably being electrically operated. A lead wire 43 connects the humidostat contact 19 to the controller (not shown) of the motor 3 and a lead wire 44 runs from the controller of motor 3 to the secondary of the transformer 34. The primary of the transformer 34 may be supplied from the usual 110 volt line through lead wires 46 and 47. In a lead wire 50 is provided a room thermostat 51 in parallel circuit with the primary of the transformer 34 for controlling the operation of the oil burner or other heat supplying apparatus to maintain a predetermined desired temperature in a room.

In series with the room thermostat 51 is a safety control device 53, which may be of any well known type, for preventing the temperature of the heat conveying medium in the furnace boiler, which may be water or steam or any other suitable medium, from being heated to an excessive degree of temperature which might result in damage to the boiler or to the heating plant in general. The control device 53 may be mounted on the furnace 1, as shown, and may be of a type which is operable in response to changes in temperature of the heat conveying medium in the furnace boiler, or of a type which is responsive to changes in pressure within the boiler. If a temperature responsive device is employed, it may be set to operate, when the temperature of the heat conveying medium in the boiler rises to a predetermined degree of temperature, to open the circuit to the burner motor 6 to decrease the burner flame. For convenience of exposition, the temperature at which the control device will operate to open the circuit to the burner motor 6 will be hereinafter referred to as 250° F. It will be understood that normally the room thermostat 51 operates, when the temperature of the room is raised to the required degree, to open the circuit to the burner motor 6, but if for some reason the room thermostat should fail to do so the safety control 75

device would act to open the circuit after the temperature of the boiler is raised to 250°. When the temperature of the boiler decreases below 250°, the control device closes the circuit. The electric blower motor 6, of the oil burner, is connected to the control device 53 by lead wire 54 and is connected to the primary lead wire 47 by means of a lead wire 55.

In parallel circuit with the room thermostat 51 and in series circuit with the safety control device 53 is a second control device 56 from which a lead wire 57 connects the same to the primary wire 46. The relay switch 33 is provided in lead wire 57, the energizing and deenergizing of the switch coil 33^a being controlled by the thermostat element 7. The control device 56, which may be termed the minimum control device, may be of any suitable well known type and like the safety control device 53, it may be of a type which is responsive to changes in boiler temperature or one which is responsive to change in pressure in the furnace boiler. The minimum control device 56 may also be mounted on the furnace, as shown, and this control device is adapted to close the circuit at its point of location in the circuit when the temperature or pressure in the boiler is below a minimum established temperature or pressure, and if the relay switch 33 is closed, the circuit will be completed to the burner motor 6 which will then be energized to operate and raise the temperature or pressure to the desired point. After the temperature of the boiler is raised to the predetermined degree for which the control device 56 is set, the control device opens the circuit at its point of location which, however, as will be seen, does not open the circuit to the motor 6 of the oil burner unless the room thermostat contact is in open circuit position. The temperature of the boiler below which the control device will close the circuit will be referred to hereinafter as 110° F.

The various lead wires associated with the control means 4 and connecting the temperature and humidity controls in the electrical circuit may be neatly arranged, as shown in Fig. 5, and be brought together adjacent the lower edge of the board 9 and be enclosed in a sheath or outer covering 28^a. In order to provide a neat appearing device and also one which may be readily moved out of the way when it is desired to wash or open the window, I provide a plug and socket connection in the lead wire. The socket, indicated at 31, may be mounted on the window sill, as shown in Figs. 3 and 6, or it may be mounted in any other suitable place and manner. By removing the plug, indicated at 31^a, it will be seen that the board 9 and controls carried thereby may be swung away from the window. In Fig. 6 the control devices, their supporting board 9 and the hinge 29, are similar to those of Fig. 3 and are arranged similarly with the control devices having a normal position adjacent the window pane and being adapted to be moved away from the window pane 10 with the hinged board, when desired. The showing of Fig. 6 differs from that of Fig. 3 in that the control devices and cooperating supporting structure are mounted on a side member of the window sash 31^b instead of on the window frame 29^a, as in Fig. 3, so as to be movable with the window. One leaf or side of the hinge 29 may be attached to the window sash 31^b such as by means of screws, or in any other suitable manner. Since the control device and supporting means are

carried by the window sash, the window may be readily raised after removing the plug 31^a.

For winter operation, the humidity control device is adjusted so as to maintain the relative humidity of the room air just under the point at which precipitation would take place on a window pane or other heat transmitting room wall surface, or maintaining the dew point temperature just under that of the window pane. By arranging the humidostat adjacent the window pane 9, it will be understood that the expansible-contractible element is affected by the moisture content of the room air but at a temperature dependent upon and variable with the outdoor temperature, or in other words, the expansible-contractible element is affected by the relative humidity of the room air at the window pane. Accordingly, if the humidostat is set so as to control the admittance of moisture to the room air, to maintain a desired substantially constant relative humidity slightly less than 100% at the window pane, the relative humidity of the room air will be maintained at a point below that at which precipitation would take place on a window pane.

It is generally agreed that for outdoor temperatures above a certain degree of temperature, artificial humidification is not necessary, and this temperature will be hereinafter referred to as 44° F., for convenience of exposition. Accordingly, the thermostat 7 is set to open the circuit to the electrically operated moisture control valve when the outdoor temperature rises to a degree of temperature such that the temperature within the room at the window pane is approximately 44° F., and is set to close the circuit when the temperature, at the window pane, decreases below 44° F. When the temperature, at the window pane, decreases below 44° F., the thermostat 7 operates to close the circuit to the motor 6 of the oil burner to raise the temperature of the room, the operation of which is hereinafter described in detail, and as is well known, when more heat is supplied to the room air the relative humidity of the room air decreases. Upon a decrease in the relative humidity of the room air, the humidostat will operate to permit the electrically operated valve 40 to open the valve port to permit moisture to be added to the room air until such time as the relative humidity, at the window pane, is raised to 98% relative humidity. Thus, it will be seen that in winter the thermostat and humidostat in connection with a heating plant, cooperate to control the humidity of the air in a heated room so as to maintain the moisture content of the room air substantially at the dew point of outdoor temperature for all outdoor temperatures below a predetermined degree, such as a temperature of 44° F. at the window pane and to maintain the room air at the highest possible relative humidity during outdoor temperatures below a predetermined degree of temperature without resultant precipitation of moisture from the room air upon the window pane.

The humidostat may be set to maintain the relative humidity at the window pane at substantially 98% relative humidity by arranging the contact 18 at a distance from contact 14 of lever 12 such that when the relative humidity decreases below 98% the expansible-contractible element 8 will have contracted sufficiently to permit engagement of the contact 14 with contact 18 and when the relative humidity rises to 98% the expansible-contractible element will have expanded sufficiently to move contact 14 out of engagement

with contact 18. This may be accomplished in the present humidostat device by pivoting the plate 17 in a direction to move contact 18 toward contact 14 and to accurately obtain the desired spacing between the contacts, the contact 18 may be adjusted in relation to contact 14 by means of the screw 21 on the end of which the contact 18 is fixed. For winter operation, the arm 22 of the thermostat 7 is spaced from the contact 25 at a distance such that arm contact 23 will make contact with the fixed contact 25 when the temperature of the room air at the window pane decreases below 44° F. Thus, for all temperatures below 44° F. at the window pane within the room, the contacts 23 and 25 will be in engagement and if the contacts 14 and 18 of the humidostat are also in engagement, the solenoid valve 40 will be energized by reason of the circuit being closed thereto through lead wires 35, 37, 42 through the solenoid lead wire 44 and back to the transformer secondary. When the solenoid is energized, the core or valve 40 is raised, thus opening the valve port in the moisture conveying pipe to permit additional moisture to be added to the room air.

If the outdoor temperature should rise to a degree of temperature such that the indoor temperature at the window pane rises to or above 44° F., then the thermostat arm 22 would tend to move away from the contact 25 and move its contact 23 out of engagement with contact 25, thus opening the circuit to the moisture supply means, or should the relative humidity of the room air at the window pane rise above 98%, the expansible-contractible element 8 would expand to move the contact arm 12 and its contact 14 out of engagement with the contact 18, and as a result, open the circuit to the moisture supply means. Thus, the humidostat and thermostat, operable in response to humidity and temperature respectively, constitute switches in an electric circuit, either of which may operate, without the other, to cause deenergization of the electrically operated moisture control device. Consequently, the solenoid valve will not be energized to admit moisture to the room air unless both the humidostat and the thermostat are in closed circuit position. If the relative humidity at the window pane is less than 98% and as a result the humidostat is in closed circuit position, the solenoid would not be energized until the temperature of the room air, at the window pane, decreased to or below 44° F. to affect the thermostat to close and complete the circuit to the solenoid.

When the outdoor temperature decreases to a degree of temperature such that the temperature of the room air at the window pane decreases below 44° F., the contacts 23 and 25 will engage and when this occurs, the relay switch coil 33^a is energized through lead wires 32, 44 and through the transformer secondary 34 and lead wire 35. Upon energization of the relay coil 33^a, the switch 33 is closed and if the temperature of the boiler is below 110°, the control device 56 has operated to close the circuit and the circuit is completed through lead wire 57, control device 53, lead wires 54 and 55 and the primary lead wire 47 to the motor 6 of the oil burner. It will be understood that on the off phase of the burner, that is, when the room thermostat is not calling for heat and the temperature of the heat conveying medium in the boiler is decreasing, when it decreases below a predetermined point, which may be taken as 110°, the heat conveying medium in the room radiators is at a still lower temperature and if permitted to continue to cool, the radiators would

become cold with the result that room air circulation would cease. It is also well known that when room air circulation ceases the air becomes stagnant or stratifies with the colder air settling at the floor of the room. Consequently, before the colder air rises and affects the room thermostat, which is for all practicable purposes located substantially midway between the floor and ceiling of a room, the room temperature and the temperature of the heat conveying medium in the boiler have continued to decrease so that when the room thermostat does demand heat there is a relatively long period of time before the boiler heat conveying medium is heated sufficiently to raise the temperature of the room to the required temperature. As a result, the heat conveying medium in the boiler is heated to a temperature in excess of that necessary to raise the temperature of the room to the temperature for which the thermostat is set and consequently the temperature of the room air is continued to be raised after the thermostat has acted to shut off the burner.

In the present system, it will be seen that the above mentioned objectionable conditions are obviated by reason of the control 56 cooperating with the thermostat 7, for if the outdoor temperature drops to a point such that the room air temperature at the window pane 10 decreases below 44°, the thermostat 7 will close the circuit, energizing the coil 33^a of the relay switch 33 and if the temperature of the boiler is below 110° the control device 56 will be in closed circuit position so that the burner motor 6 is energized to raise the temperature of the boiler to 110° F. Any suitable minimum temperature may be selected, the temperature of 110° F. being herein used for convenience of exposition. Preferably the minimum temperature selected is such that the heat conveying medium in the boiler will be limited to a degree of temperature just below the boiling point for a steam heating system or in a hot water system to a temperature which will prevent the radiator in the room from becoming cold and therefore prevent resultant stagnation of the room air.

The control device 56 is thus arranged to act in anticipation of a demand for room heat, when the outdoor temperature decreases and when the temperature of the boiler is below a predetermined degree of temperature. By maintaining the circulation of the room air, it will be understood that the heat thereof is more evenly distributed throughout the room with the result that the room thermostat would be affected sooner upon a decrease in room air temperature than would be the case if the air had become stratified or stagnant. Also, since the temperature of the boiler has been raised to 110°, the time period necessary for the burner to raise the temperature of the heat conveying medium to the point at which the temperature of the room will be raised to the required temperature will be relatively short and as a result, the temperature of the boiler will not be raised to a degree of temperature in excess of that necessary for raising the temperature of the room to the desired degree so that the temperature of the room will not rise substantially above the desired temperature for which the room thermostat is set.

For summer operation, the humidifying apparatus may be dispensed with by opening the circuit by means of the switch 42^a to the moisture control valve, since it is generally agreed that artificial humidification is not necessary when

the outdoor temperature rises to, or above, a certain degree of temperature which may be taken as approximately 44° F. However, even if the manual switch is left in closed circuit position, the moisture control valve will not be energized, for above a temperature of 44° F., the contacts 23 and 25 of the thermostat, which are in series circuit with the control valve 2, will not be in engagement. When the temperature rises to approximately 80° F. outdoor temperature or above, it is also well known that artificial dehumidification is desirable in order to maintain a desired relative humidity of the air in a room, for comfort. In the present system, the thermostat and humidostat are adapted to control the operation of the dehumidifier motor 3 in accordance with outdoor temperature and the relative humidity of the room air at the window pane respectively, to maintain a desired relative humidity of the air in a room. For summer operation, the plate 17 is pivoted in a direction so as to move the contact 19 toward the contact 15 of the arm 12, to obtain a space therebetween such that the expansible-contractible element 8 will move the arm contact 15 into engagement with contact 19 when the relative humidity at the window pane is at, or above, a desired point, for example 50% relative humidity at the window pane. The contact 24 of the thermostat arm 22 is arranged relative to the contact 26 so that it will engage therewith when the outdoor temperature rises to a temperature at which artificial dehumidification is desired, which temperature may be assumed to be 80° F. Accordingly, if the relative humidity of the room air at the window pane increases to or above 50% relative humidity, the expansible-contractible element 8 will expand and move the contact 15 into engagement with the contact 19 and if the outdoor temperature is at 80° F. or, so that the contact 24 is in engagement with contact 26, then the circuit is closed to the controller of the motor 3 through lead wire 35, the secondary of transformer 34, lead wire 44 and lead wires 38 and 43. When the circuit is thus closed to the controller of the motor 3, the motor operates the dehumidifying apparatus, which apparatus may be of the type which supplies dehumidified air to the room or of the type which operates on the condensator principle, or any other suitable type. When the relative humidity of the room air at the window pane is decreased to 50% or lower, the expansible-contractible element 8 contracts, breaking engagement between the contacts 15 and 19 and thus opening the circuit to the controller of the motor 3, or when the temperature of the room air at the window pane decreases below 80° F., the thermostat 7 will operate to open the circuit to the controller of the motor 3.

Referring now to Fig. 2, there is shown an air conditioning system similar to the system shown in Fig. 1, except that a different type of humidostat is employed and one which is automatic in that adjustment is not necessary when changing from winter to summer operation or vice versa. This humidostat, like that of Fig. 1, includes a pivotal contact arm or switch 58, an expansible-contractible element 59 for operating the arm, and a spring 60 for maintaining the arm 58 in engagement with the expansible-contractible element 59. On the free end of the arm 58 are provided contacts 61 and 62, one on each side thereof, for engaging contacts 63 and 64 respectively. The contacts 63 and 64 in this humidostat are mounted on the free ends of spaced

pivotal arms 65 and 66 respectively which are mounted on the board 9 and preferably arranged in relation to arm 58 so that the free ends of the arms 58, 65 and 66 are adjacent each other with the contacts 61 and 62 of arm 58 between and in alignment with the contacts 63 and 64 of levers 65 and 66 respectively. A spring 67 is provided for urging the pivotal levers 65 and 66 toward each other. The levers 65 and 66 are each provided with an adjustable stop 68 and 69 respectively which may be screws, as shown, threaded into fixed bracket members mounted on the board 9. The stops or screws 68 and 69 are arranged between the pivotal levers 65 and 66 so that the ends of the screws are in position to bear against the adjacent sides of the lever arms 65 and 66 and toward which the spring 67 under tension tends to move the lever arms. The lever arm 65 cooperates with the lever arm 58 to control the operation of the humidifying means for winter operation while the lever arm 66 cooperates with the arm 58 for controlling the dehumidifying means for summer operation.

Mounted on the board 9 is a bimetallic temperature responsive element 70 having one end fixed to the board 9, such as by a bracket 72, the other end 71 being free and in the form of a switch arm for movement in response to changes in temperature at the window pane. The arm is provided with a pair of contacts 73 and 74 which are fixed thereto on opposite sides of the arm and near the end thereof. Contacts 75 and 76 are mounted on the board 9, one on each side of the arm 71 for engaging with contacts 73 and 74 respectively. Preferably, the contacts 75 and 76 are adjustable and to this end, the contacts may be mounted on the ends of screws 77 which are threaded in brackets 78 mounted on the board 9. For winter operation, the contact 75 is positioned relative to contact 73 of the temperature responsive element a distance such that the contact 73 will engage contact 75 when the temperature at the window pane is at or decreases below a predetermined degree of temperature, which may be taken as before at 44° F. The contact 76 is spaced from the contact 74 of arm 71 such that when the temperature at the window pane increases to or exceeds a predetermined degree of temperature, which may be taken at approximately 80° F., arm 71 will have moved sufficiently so that its contact 74 will engage contact 76 and when the temperature at the window pane decreases below 80° F., contact is broken. The contact 76 of the temperature responsive element is connected to the controller of the dehumidifier motor 3 by means of a lead wire 81 and the contact 64 of the humidostat is connected to the dehumidifier motor 3 by means of a lead wire 82. The temperature responsive element 70 is connected by the lead wire 35 to the secondary of the transformer 34 and the arm 58 of the humidostat is connected to the transformer secondary by means of a lead wire 84. The thermostat 70 and humidostat thus being in series circuit so that the dehumidifier motor is not energizable to dehumidify the air of a room unless the circuit thereto is closed by both the thermostat 70 and the humidostat. Or in other words, the dehumidifier motor 3 is not energized unless the temperature at the window pane is above 80° F., and the relative humidity of the room air at the window pane is above 50%.

The humidostat and thermostat are also in series circuit with the magnetically operated con-

5 trol valve 2 for controlling the admittance of moisture to a room in winter. The moisture control valve is connected by means of a lead line 86 to the contact 63 of the lever 65 and to the contact 75 of the thermostat element by means of lead wires 87 and 88 in which a manually operated switch 89 may be provided, if desired. If the temperature at the window pane is below 44° F., the thermostat will close the circuit through 10 energization of the relay switch coil 33a to the minimum control device 56. If the temperature in the boiler is below 110° F., then the circuit is closed to the burner motor 6 and the temperature of the boiler raised to 110° F., in anticipation of the operation of room thermostat to close the circuit through control 53 because of decrease in outdoor temperature. The temperature of the boiler is thus prevented from decreasing to an excessive low degree of temperature and sufficient heat is supplied to maintain room air circulation so that the heat of the room is thoroughly distributed with the result that the room thermostat will be affected sooner than it would be if the air of the room was permitted to stratify. If the relative humidity of the room air at the window pane is below 98%, which is likely after heat is supplied to the room, the control device 2 will be energized, opening the valve port to admit moisture to the air. It will be seen that if either the temperature at the window pane increases above 44° F., or the relative humidity increases about 98%, that the circuit to the moisture control valve will be broken thus stopping the flow of moisture to the room air.

20 30 35 40 45 50 55 60 65 70 The operation of the automatically adjustable humidostat of the air conditioning system of Fig. 2 is as follows: When the outdoor temperature decreases below a predetermined temperature, which may be taken as before at 44° F., artificial humidification of the air of a room may be necessary to the comfort of persons therein while for temperatures above the predetermined outdoor temperature, artificial humidification is not necessary. Accordingly, the temperature responsive element 70 is arranged to move its contact 73 into engagement with its cooperating contact 75, in the circuit of the moisture supply means, when the outdoor temperature decreases below the predetermined temperature of 44° F. The desired relative humidity of the room air to be maintained for all outdoor temperatures below 44° F., is, of course, approximately 100% relative humidity at the window pane but slightly less than 100% or say 98% so that condensation of room air moisture will not take place on a window pane or other heat transmitting room wall surface. Accordingly, contacts 63 and 61 of the humidostat, which are in circuit with the moisture control means 2, are arranged to part and open the circuit to the moisture supply means to discontinue the supplying of moisture to the room air when the relative humidity thereof increases to approximately 100% relative humidity. Since the contacts 73 and 75 of the thermostat and the contacts 61 and 63 of the humidostat are in series circuit with the moisture supply control means 2, it will be seen that additional moisture will not be supplied to the room air unless the contacts of the thermostat and also the humidostat are in closed circuit position. As a result, the opening of either set of contacts opens the circuit to the moisture supply control means whereupon the supplying of moisture to the room air will be discontinued.

75 As previously stated, if the outdoor tempera-

ture decreases below a temperature of 44° F., the contacts 73 and 75 of the thermostat will be in engagement, and if the contacts 61 and 63 of the humidostat are in engagement, then additional moisture will be supplied to the room air. When the relative humidity of the room air at the window pane decreases below the desired relative humidity or approximately 100% relative humidity, then the expansible-contractible element 59 will contract permitting the spring 60 to move the arm 58 in a clockwise direction, as seen on the drawings. Since the contact 63 of pivot arm 65 is in engagement with contact 61 of arm 58 for all values of relative humidity less than the desired relative humidity of approximately 100% relative humidity, the arm 65 will be pivoted by the spring 60 through engagement with arm 58. The arm 65 will then be moved away from its stop member 68 as shown in Fig. 5.

As the relative humidity of the room air is increased, the moisture absorption element 59 expands and moves the pivoted arm 58 in a counter-clockwise direction, as seen on the drawings. As the arm 58 is moved by the element 59, the arm 65 is drawn toward its contact 68 by the spring 67 and the contacts 63 and 61 of the pivoted arms are held in engagement by the spring 67. When the relative humidity of the room air surrounding the element 59 is substantially but less than 100% relative humidity, the arm 65 will be in engagement with its stop member 68 after which additional movement of arm 58 will result in the parting of the contacts 61 and 63 and, therefore, the discontinuing of the supplying of moisture to the room air.

When the outdoor temperature rises above a predetermined temperature which may be taken as before at 80° F., then artificial dehumidification of the air of a room may be necessary to the comfort of persons therein. Accordingly, the thermostat 70 is arranged to move its contact 74 into engagement with cooperating contact 76, the contacts 74 and 76 being in circuit with the dehumidifying device 3. The desired relative humidity of the room air may be determined and which will here be referred to as before as 50% relative humidity, for convenience of exposition, although a lower relative humidity may be desired. The contact 82 and the contact 64 of the humidostat are arranged relative to each other and to the stop member 69 so that the contacts will engage when the relative humidity of the room air at the humidostat is 50% relative humidity. At this point it will be noted that between 100% and 50% relative humidity contacts 61 and 62 will both be in engagement with their respective contacts 63 and 64. However, it will be seen that both the moisture supply control means and the dehumidifying means will not be energized for only one of the pairs of cooperating contacts of the thermostat will be in engagement depending upon the temperature of the outdoor atmosphere. When the outdoor temperature increases above a temperature of 80° F., contacts 74 and 76 of the thermostat will be in engagement and if the relative humidity of the room air surrounding the humidostat is above 50% relative humidity then contacts 62 and 64 of the humidostat will be in engagement through movement of the arm 58 due to the expansion of the element 59. As a result, the circuit of the dehumidifying device will be closed whereupon the dehumidifying device will act to reduce the relative humidity of the room air. When the relative humidity of the room air has been re-

duced to 50% relative humidity, the circuit to the dehumidifying device will be broken after engagement of arm 65 with its stop member 68.

It will be noted that between outdoor temperatures from 44° F. to 80° F., conditioning of the room air is not necessary to the comfort of persons therein while below and above these temperatures the room air is humidified and dehumidified respectively.

From the foregoing description, it will now be seen that I have provided a new and improved method of and apparatus for conditioning the air of a room or other enclosed space. By utilizing a thermostat and a humidostat arranged to cooperate in controlling the admittance of moisture to the air of a room in accordance with decrease in outdoor temperature below a predetermined degree of temperature, and decrease in relative humidity of the room air at outdoor temperature, respectively, it will be appreciated that the room air will be maintained at the highest possible relative humidity without danger of precipitation of room air moisture on a window pane. In addition, it will be appreciated that when the outdoor temperature decreases below the predetermined degree of temperature, the thermostat in cooperation with the minimum control device prevents the radiators in a room from becoming cold to prevent stagnation or stratification of the room air. The advantages of maintaining gravity circulation of the air in a room is that the heat in the room is more evenly distributed by the moving air so that at the level of the thermostat in the room the air is more representative of the general condition of the air throughout the room than it would be if the air was permitted to stratify with the colder air at the floor. Furthermore, since the temperature of the heat conveying medium in the boiler is brought up to a degree of temperature, for example 110°, necessary to maintain the radiators warm when the outdoor temperature decreases below a certain degree of temperature, it will be appreciated that a demand for heat by the room thermostat is anticipated. Consequently, when the room thermostat does demand heat, it will be understood that a shorter time period will be required by the burner to raise the temperature of the boiler to the required degree of temperature necessary to satisfy the room thermostat than would be the case if the boiler temperature had decreased to the point where the room radiators would be cold. Furthermore, by reason of the fact that the boiler temperature can be quickly raised to the required temperature to satisfy the room thermostat, it will be appreciated that the heat conveying medium in the boiler will not be raised to a degree of temperature which would cause undue increase in room temperature after the thermostat is satisfied. Another advantage of the present invention resides in the method of and apparatus for maintaining the relative humidity of the air in a room at the desired relative humidity for comfort for all outdoor temperatures above a predetermined degree of outdoor temperature. In addition, I have provided apparatus for maintaining the relative humidity of a room at the desired percent for both winter and summer and which is automatic in that no adjustment is necessary when changing from summer to winter or vice versa. Furthermore, I have provided for arranging the thermostat and humidostat controls in relation with a window pane or other heat transmitting room wall surface in a new and improved manner whereby the thermostat is affected by

changes in outdoor temperature and the humidostat is affected by the moisture content of the room air but at outdoor temperature.

What I claim and desire to secure by Letters Patent of the United States is:

1. The method of controlling the moisture content of the air in a room or other enclosed space which comprises raising the moisture content of the air in the room substantially to the dew point of the outdoor atmosphere for all outdoor temperatures below a predetermined degree of temperature, and discontinuing the supply of moisture to the air for outdoor temperatures above said predetermined degree whereby to maintain the room air at the highest possible relative humidity during outdoor temperatures below said predetermined degree without substantial precipitation of moisture from the room air upon a window pane or other heat transmitting room wall surface.

2. The method of controlling the moisture content of the air in a room or other enclosed space which comprises raising the moisture content of the air in the room substantially to the dew point of the outdoor atmosphere for all outdoor temperatures below a predetermined degree of temperature, discontinuing the supply of moisture to the air for outdoor temperatures above said predetermined degree whereby to maintain the room air at the highest possible relative humidity during outdoor temperatures below said predetermined degree without substantial precipitation of moisture from the room air upon a window pane or other heat transmitting room wall surface, and at a second predetermined outdoor temperature above said first-named predetermined temperature decreasing the relative humidity in the room or space.

3. The method of regulating the temperature and moisture content of the air in a room which comprises supplying a heated heat transfer medium to the room when room air temperature is below a predetermined degree, establishing a predetermined minimum temperature of the heating medium for all outdoor temperatures below a predetermined degree to provide circulation of the room air and simultaneously with the establishing of said minimum predetermined temperature supplying moisture to the room air for circulation therewith to raise the moisture content of the room air substantially equally over the entire air content of the room and to a quantity corresponding to 100% relative humidity for the then prevailing outdoor temperature.

4. In an air conditioning system for controlling the moisture content of the air of a room or other enclosed space, a humidostat exposed to room air and operable to control supply of moisture to the room air, means to provide the room air to which the humidostat is exposed with a temperature substantially equal to and variable in accordance with outdoor temperature, and means responsive to outdoor temperature and operable upon occurrence of a predetermined low outdoor temperature to render said humidostat effective to supply moisture to the air of the room or other enclosed space, said responsive means being operable to render said humidostat ineffective upon an increase in outdoor temperature above said predetermined low temperature.

5. In an air conditioning system for controlling the moisture content of the air of a room or other enclosed space, means including a humidostat operable in response to decrease in the moisture content of a portion of the room air

below a predetermined percent of relative humidity to admit moisture to the room air, means to cool the air portion substantially to the prevailing outdoor temperature, and thermal responsive means responsive to an increase in outdoor temperature above a predetermined degree for discontinuing the admittance of moisture to the room air whereby to maintain the room air at the highest possible relative humidity for all outdoor temperatures below said predetermined degree without resultant precipitation of moisture from the room air upon a window pane or other heat transmitting room wall surface.

6. In an air conditioning system for conditioning the air of a room or other enclosed space, means operable to control admission of moisture to the air of the room or other enclosed space, a humidostat responsive to the moisture content of a portion of the air in the room or other enclosed space and controlling said means, means to cool the portion of the room or space air to substantially the prevailing outdoor temperature thereby to maintain the moisture content of the room air substantially at the same dew point as the outdoor temperature, and temperature responsive means operable upon occurrence of a predetermined high outdoor temperature to render said humidostat ineffective to control admittance of moisture to the air of the room or other enclosed space, said first-named means being operable to admit moisture to the air of the room or other enclosed space only when both said humidostat and said temperature responsive means are calling for moisture.

7. In a system for conditioning the air of an enclosed space, electrically operated means to control admittance of moisture to the air of the enclosed space, switch means to control said electrically operated means, an expansible-contracible element responsive to the moisture content of a portion of the air in the enclosed space and operable to actuate said switch means, means to cool the air portion to a temperature substantially equal to the prevailing outdoor temperature, and a thermostat responsive to outdoor temperature and in series circuit with said switch means, said thermostat being operable on predetermined decrease in outdoor temperature to increase the moisture content of the air in said space only when said switch means is in closed circuit position.

8. In an air conditioning system for conditioning the air of a room or other enclosed space, means operable for controlling the admittance of moisture to the room air, a humidostat within the room and at a window pane thereof operable in response to a decrease in relative humidity at the window pane below a predetermined percent for controlling the operation of said means, and a thermal responsive element operable in response to an increase in outdoor temperature above a predetermined degree of temperature to render said humidostat ineffective for maintaining the room air at the highest possible relative humidity and operable upon a decrease below said predetermined degree to render said humidostat effective for all outdoor temperatures below said predetermined degree to maintain the room air at the highest possible relative humidity without substantial precipitation of moisture from the room air upon the window pane or other heat transmitting room wall surface.

9. In a system for controlling the moisture content of the air in an enclosed space, means operable to dehumidify the air in the enclosed

space, a humidostat responsive to the moisture content of the room air to control said dehumidifying means, and temperature responsive means operable in response to outdoor temperature to control said dehumidifying means, said humidostat being ineffective to decrease the moisture content of the air in the enclosed space at outdoor temperatures below a predetermined temperature.

10. In an air conditioning system for controlling the moisture content of the air in a room or other enclosed space, means for controlling the admittance of a dehumidifying medium to the room air, a humidostat disposed within the room and adjacent a window pane thereof so as to be subjected to substantially outdoor temperature due to the transfer of heat through the window pane, said humidostat being operable in response to an increase in the relative humidity of the air at the window pane to control said means, and thermal responsive means operable in response to increase in the outdoor temperature for controlling said means to increase the admittance of the medium.

11. An air conditioning system for a room or other enclosed space comprising means for varying a condition of the air in said space, a second means for varying a different condition of the air in said space, and controlling means operable upon occurrence of a predetermined temperature of the air external of said space for substantially simultaneously rendering effective said first-named means and said second-named means.

12. An air conditioning system for a room or other enclosed space comprising means for varying a condition of the air in said space, means for automatically regulating said condition varying means, a second means for varying a different condition of the air in said space, means for automatically regulating said second-named condition varying means, and controlling means operable upon a predetermined temperature of the air external of said space for substantially simultaneously rendering ineffective said first-named means and said third-named means.

13. An air conditioning system for a room or other enclosed space comprising means for varying a condition of the air in said space, means for automatically regulating said condition varying means, a second means for varying a condition of the air in said space, means for automatically regulating said second-named condition varying means, controlling means operable upon occurrence of predetermined temperature external of said space to discontinue operation of said first-named means and said third-named means, and means for initiating operation of said first-named means irrespective of operation of said controlling means.

14. In an air conditioning system for a room or other enclosed space, a casing having inlet and outlet openings for the passage of air through said casing, said casing having one wall of high heat conductivity exposed to atmosphere external of said space, a thermostat in said casing and operable in accordance with variation in temperature external of said space, a humidity responsive device in said casing operable in accordance with the humidity of the air in said space at the temperature of the air in said casing, an apparatus for supplying heat to said space to maintain circulation of the air in the enclosed space and having a controlling circuit, an apparatus for supplying moisture to said space and having a controlling circuit, said humidity re-

sponsive device controlling the circuit of said moisture supplying means, and said thermostat acting to control irrespective of operation of said humidity responsive device the circuit of said moisture supplying apparatus and simultaneously acting to control the circuit of said heat supplying apparatus to insure a circulation of air so that the moisture from said moisture supplying apparatus is distributed throughout the enclosed space.

15. In an air conditioning system for a room or other enclosed space, a casing having inlet and outlet openings for the passage of air through said casing, said casing having one wall of high heat conductivity exposed to atmosphere external of said space, a thermostat in said casing and operable in accordance with variation in temperature external of said space, a humidity responsive device in said casing operable in accordance with the humidity of the air in said space at the temperature of the air in said casing, an apparatus for supplying heat to said space to maintain a circulation of the air in the enclosed space and having a controlling circuit, an apparatus for supplying moisture to said space and having a controlling circuit, said humidity responsive device controlling the circuit of said moisture supplying means to maintain the relative humidity substantially at but slightly below one hundred per cent, said thermostat acting to control irrespective of operation of said humidity responsive device the circuit of said moisture supplying apparatus to discontinue at a given temperature the operation of said moisture supplying apparatus and simultaneously acting to control the circuit of said heat supplying apparatus so that air circulation will be established within the enclosed space during the time moisture is being supplied, an apparatus for dehumidifying the air in said space and having a controlling circuit, said thermostat acting upon rise of temperature above the temperature at which said moisture supplying apparatus is discontinued to establish the controlling circuit of said dehumidifying apparatus, and said humidity responsive device controlling the circuit of said dehumidifying apparatus under the domination of said thermostat.

16. The method of regulating the condition of the air within an enclosed space comprising the supplying of water vapor to the enclosed space to maintain a dew point temperature within the space just below the temperature of a wall surface having a high rate of heat transfer, rendering said supply effective upon the attainment by the wall of a predetermined minimum temperature, and establishing circulation of the air within the enclosed space so that the supplied water vapor will be evenly distributed to the circulated air and throughout the enclosed space.

17. In a control system for a space having a window, the combination of humidifying means and heating means for the space, the condition of the space adjacent the window varying in accordance with changes in the condition outside of the space, and means located adjacent the window and responsive to the condition of the space adjacent the window for controlling the humidifying means and the heating means.

18. In a control system for a space having a window, the combination of, humidifying means and heating means for the space, means responsive to space temperatures for controlling said heating means, the condition of the space adjacent the window varying in accordance

with changes in the condition outside of the space, and means including means located adjacent the window and responsive to the condition of the space adjacent the window for controlling the humidifying means and additionally controlling the heating means.

19. In a control system for a space having a window, the combination of, humidifying means and heating means for the space, the relative humidity of the space adjacent the window varying in accordance with changes in the condition outside of the space, and means including means located adjacent the window and responsive to the relative humidity of the space adjacent the window for controlling the humidifying means, said third-named means also including means for controlling the heating means.

20. In a humidity control system for a space, the combination of humidifying means for the space, means responsive to the relative humidity of a portion of the space for controlling the humidifying means, the temperature of said portion of the space being altered by variations in a condition outside of the space, and means responsive to the temperature of said portion of the space for rendering the humidity responsive means ineffective to control the humidifying means.

21. In a control system for a space, the combination of humidifying means for the space, heating means for the space, means responsive to space temperature for controlling said heating means, and means responsive to the condition of the space which is affected by a condition outside of the space for controlling said humidifying means and additionally controlling said heating means independently of said first-named responsive means.

22. In a control system for an enclosed space, means for changing the temperature of the space, means for changing the humidity of the space, control means sensitive to the temperature of the space and operable to control said first-named means, means within the space and responsive to the space air at a temperature proportional to the temperature external of the

space for controlling said first-named means independently of said control means and for controlling said second-named means.

23. In a control system for an enclosed space, 5 a first means for changing the temperature of the space, a second means for changing the moisture content of the space, means within a first portion of the space and sensitive to the air condition within the space and operable to control said first means, means independent of said first-named sensitive means and positioned within a second portion of the space separate from said first portion, said independent means being sensitive to the temperature of the space air in said second portion and operable to control one of said changing means, the temperature of the air in said second portion being at a temperature variable with the temperature external of the space.

24. In a control system for an enclosed space, 10 a first means for changing a condition of the space, a second means for changing a condition of the space, means within a first portion of the space and sensitive to the air condition within the space and operable to control said first means, means independent of said first-named sensitive means and positioned within a second portion of the space separate from said first portion, said independent means being sensitive to the temperature of the space air in said second portion and operable to control both of said changing means, the temperature of the air in said second portion being at a temperature variable with the temperature external of the space.

25. In a control system for an enclosed space, 15 means for humidifying the space, means for heating the space, humidity responsive means within the space and controlling said humidifying means, temperature sensitive means within the space and operable to control said heating means to maintain a predetermined temperature in the space, and means independent of said temperature sensitive means and positioned within the space and sensitive to changes in temperature external of the space for controlling said first-named and second-named means.

PHILIP SHERMAN RUSSEL.
